UNITED STATES PATENT OFFICE.

CHARLES M. SCHWAB, OF MUNHALL, PENNSYLVANIA.

APPARATUS FOR MANUFACTURING AXLES.

SPECIFICATION forming part of Letters Patent No. 599,638, dated February 22, 1898.

Application filed December 16, 1896. Serial No. 615,908. (No model.)

To all whom it may concern:

Be it known that I, CHARLES M. SCHWAB, of Munhall, in the county of Allegheny and State of Pennsylvania, have invented a new and useful Improvement in Apparatus for Manufacturing Axles, of which the following is a full, clear, and exact description, reference being had to the accompanying drawing, forming part of this specification, in which 5 **10** the figure is a diagrammatic plan view showing my improved apparatus for the manufacture of axles and similar articles.

My invention relates to the forming of axles by hammering them into shape from billets 15 or pieces of steel. Heretofore in presenting the piece of steel to the hammer the ordinary rectangular or square billet has been employed, and the capacity of the hammer is very much reduced by the use of such square 20 or rectangular billet.

My invention is designed to greatly increase the capacity of the hammer and reduce the cost of the axle, as well as to improve the quality of the steel; and to that end it consists, broadly, in placing between the heating-furnace and the hammers a pair of rolls 25 by which the square billet may be reduced to a round or cylindrical form before it passes to the hammers.

30 In the drawing, in which similar numerals indicate corresponding parts, 2 represents the heating-furnace, in which the square billet is brought to a proper temperature and from which it is taken by any suitable device, such as a truck moving on a track 3, to the roller-table 4 of a set of reducing-rolls 5, through which the metal passes and in which it is reduced at a single pass from a square to a round billet. The round billet emerges 35 40 on a roller-table 6, from which it is taken by a suitable appliance—such as a truck moving

on a track 7, an overhead crane, or similar device—to one of several hammers 8, by which the round billet is finished into an axle.

The advantages of my invention will be apparent to those skilled in the art, since the square billet is reduced to a cylindrical form in the rolls, which do part of the work ordinarily accomplished by the hammers, and the forging is then finished under the hammer at 45 50 the same heat. The capacity of the hammers is thereby greatly increased, while the cost of the axle is reduced and its quality improved.

It is evident that the rolling-mill or rolling device may be of any desired construction 55 and operated by either steam, electricity, or hydraulic pressure, and the billet may be reduced by either one or more passes, so as to produce a round billet from a square one, 60 and many other changes may be made in the form and arrangements of the parts without departing from my invention, since I consider myself the first to combine with a hammer for forming axles or similar articles a rolling-mill by which the square billet is reduced to 65 70 a round before passing to the hammers, the operation being accomplished without the necessity of reheating.

I claim—

In the manufacture of axles or similar articles, the combination with rolls arranged to reduce a heated square billet to substantially cylindrical form before forging, of a hammer arranged to receive the cylindrical billet from 75 the roll and forge the same into final form.

In testimony whereof I have hereunto set my hand.

CHARLES M. SCHWAB.
